CLAIM

We claim the ornamental design for a speaker system for bath and shower environments, as shown and described.

DESCRIPTION

FIG. 1 is a perspective view of a speaker system for bath and shower environments, showing our new design;
FIG. 2 is a front view of the embodiment of FIG. 1;
FIG. 3 is a rear view of the embodiment of FIG. 1;
FIG. 4 is a side view of the embodiment of FIG. 1;
FIG. 5 is another side view of the embodiment of FIG. 1;
FIG. 6 is a top view of the embodiment of FIG. 1; and,
FIG. 7 is a bottom view of the embodiment of FIG. 1.
The dash-dot broken lines immediately adjacent the shaded areas represent the bounds of the claimed design while all other broken lines are included for the purpose of illustrating portions of the speaker system for bath and shower environments; the broken lines form no part of the claimed design.
